(57) **CLAIM**

We claim the ornamental design for a washing machine with full-touch LCD having graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a washing machine with full-touch LCD having graphical user interface showing our new design; and,

FIG. 2 is an enlarged view thereof, but shown without broken lines for ease of illustration.

The broken lines shown in the drawings represent the washing machine with full-touch LCD that form no part of the claimed design.
